UNITED STATES PATENT OFFICE

172,363

CARD HOLDER

Ed Rosenbaum, Ogontz, Pa.

Application December 8, 1953, Serial No. 27,980

Term of patent 7 years

(Cl. D1—3)

To all whom it may concern:

Be it known, that I, Ed Rosenbaum, a citizen of the United States, residing at Ogontz, State of Pennsylvania, have invented a new, original, and ornamental Design for a Card Holder, of which the following is a specification, reference being had to the accompanying drawing, forming a part hereof:

Fig. 1 is a front perspective view of a card holder showing my new design; and

Fig. 2 is a vertical sectional view thereof.

I claim:

The ornamental design for a card holder, as shown.
